UNITED STATES PATENT OFFICE.

MALCOLM D. RIKER, OF DOVER, NEW JERSEY, ASSIGNOR TO MCKIERMAN-TERRY
DRILL COMPANY, A CORPORATION OF NEW JERSEY.

LIFTING-JACK.

1,366,332.

Specification of Letters Patent.

Patented Jan. 18, 1921.

Application filed December 26, 1918. Serial No. 268,347.

To all whom it may concern:

Be it known that I, MALCOLM D. RIKER, a citizen of the United States, and a resident of Dover, Morris county, and State of New Jersey, have invented certain new and useful Improvements in Lifting-Jacks, of which the following is a specification, reference being had to the accompanying drawings, forming a part thereof.

10 This invention relates to new and useful improvements in lifting jacks of the screw type, and its object is to provide a device of great strength, few parts and of such construction that its parts are assembled 15 without the use of screws, nuts or rivets.

Another object is to so arrange and construct the device that it may be taken apart and assembled without the use of tools.

Another object is to provide a simple and 20 effective stop for limiting the lifting movement of the jack.

In order that my invention may be thoroughly understood I will now proceed to describe the same in the following specification and will then point out the novel features thereof in appended claims.

Referring to the drawings:

Figure 1 is a sectional elevation of a jack which is made according to and embodies 30 this invention. The plane on which this section is taken is indicated by the line 1—1 of Fig. 3.

Fig. 2 is a plan view of the same device.

Fig. 3 is a sectional plan view of this improved jack, the section being taken on the line 3—3 of Fig. 1.

Fig. 4 is a sectional elevation of a ratchet mechanism which forms a part of this apparatus. The section in this figure is taken 40 on the line 4—4 of Fig. 5.

Fig. 5 is a sectional plan view of this ratchet mechanism illustrating the manner in which its parts are assembled. This section is taken on the line 5—5 of Fig. 4.

Fig. 6 is a sectional elevation taken on the line 6—6 of Fig. 2, to illustrate a detail of construction,—a locking pin for holding parts of the device together.

Fig. 7 is a sectional elevation taken on 50 the line 7—7 of Fig. 6 to show a lifting foot or projection.

Like characters of reference designate corresponding parts in all the figures.

10 designates an inner member, the lower 55 end 11 of which is constructed to form a

base. Above the base the outer surface 12 of this member is cylindrical. A central bore in the upper end of member 10 receives a nut 13, and keys 14 are provided to prevent rotation of this nut.

15 is a collar screwed onto the upper end of member 10 having a cylindrical outer surface 16 of somewhat larger diameter than that of the surface 12, and a lower beveled end 17.

The lifting screw 20 fits the nut 13 and extends through the inner member 10. 21 is an upper cylindrical extension of the lifting screw near the upper end of which is an annular groove 22. 23 is a worm gear 70 surrounding the extension 21 and connected with the lifting screw by keys 24. Above gear 23 is an anti-friction thrust bearing 25.

The outer member comprises a cylindrical shell 30, the lower inner part of which 75 is turned to form a cylindrical surface 31 which forms a sliding fit with the surface 12. Above this surface is a longer finished cylindrical surface 32 which forms a sliding fit with the collar surface 16. Between 80 the surfaces 31 and 32 is a beveled shoulder 33.

The upper end of the outer member forms a head 34 in the center of the under side of which is a cylindrical pocket which receives the extension 21. Below this head is an opening 35 slightly wider than the diameter of the gear 23 and higher than the diameter of the worm 50. 36 is a plate of spring metal which closes this opening and 90 is retained in position by its vertical edges being sprung into grooves 37 at the sides of the opening. At 38 the metal of the outer member is cut away to afford a finger hold on the plate. By bending the plate outwardly into the position indicated by the dotted lines at 36^A in Fig. 3, it may be removed. 39 are lugs formed under the head 34 to hold the thrust bearing 25 in a central position and thus help to hold the lifting screw in axial alinement with the nut 13.

Opposite the opening 35 the outer member form a transverse housing 40 with parallel vertical walls 41, 42. On an oblique axis A, A a clearance hole 43 for the 105 larger part 51 of the spindle of worm 50 is drilled through the wall 41 and a smaller hole 44 is drilled through the same wall on the axis B, B to form a bearing for a smaller part 52 of the same spindle. The 110

inner end of the worm is formed with a cylindrical boss 53 which fits a bearing pocket in wall 42 in axial alinement with the hole 44 and which is cut away on one side semi-cylindrically in alinement with line A, A as shown at 45. 54 is a thrust member between the end of the worm 50 and the housing wall 42.

When the worm 50 is placed in the housing 40, it may be placed in alinement with the line A, A and its spindle inserted in a bore provided in the worm for its reception. Then the spindle and worm are moved into axial alinement with the line B, B. In this position the worm is in position to mesh with gear 23 and the shoulder between the parts 51 and 52 of the spindle will engage the inner surface of the housing wall 41 to prevent an outward movement of the spindle. A key between the spindle and the worm is designated by the reference numeral 55.

With the worm in position and the outer member raised to bring the axis of the worm above the top of the extension 21, the gear 23 and thrust bearing 25 may be inserted through the opening 35. Then the outer member is lowered to the position shown in Fig. 1, with extension 21 passing through gear 23, thrust bearing 25 and into the pocket under the head 34.

A radial groove 26 is provided under the head 34 to support a slide 27, the inner end of which projects into the groove 22 to lock the parts together. The opposite end 28 of the slide is bent downwardly to facilitate its removal and intermediate its ends it is humped as at 29 to engage a depression in groove 26, which prevents its accidental displacement.

The manner of assembling this device which has just been described, is simply reversed for taking it apart. This may be accomplished readily in the field and without tools, so that the parts are at all times accessible for inspection or repairs.

The ratchet device comprises a toothed member 60 which fits the spindle part 52. Keys between these parts are shown at 57. 50 A circular hub 61 of this member fits a similarly shaped opening in a housing 62 which is a malleable casting having lugs 63 which space the toothed part of member 60 from its inner surface. The housing casting forms a radial socket 64 for the reception of an actuating lever, and a handle 65 by means of which it may be rotated. It also forms a radial pocket 66 in which is a spring-pressed pawl 70. The 60 housing casting comprises a cover 67 having a circular opening for the reception of a hub on member 60. This cover is raised as in Fig. 5 to permit the insertion of member 60 and the pawl 70, and after these 65 parts are put in place the cover is bent down

against lugs 68 which serve as stops and other lugs 69 are then bent down over it as shown in Fig. 3, to hold it in place.

The pawl 70 is pressed inwardly by a spring 71 and has a part 72 which protrudes through the housing by means of which it may be reversed to bring its inner beveled end into the relation to the teeth of member 60 in which it is shown in Fig. 4 or in the opposite relation. Thus an oscillating movement of the housing will cause a step by step rotation of the member 60 and worm 50 in one direction or the other, to cause the outer member 30 to move up or down. When the outer member has moved upwardly as far as it should go, its beveled shoulder 33 abuts against the beveled under surface 17 of the collar 15. This arrests further upward movement and forms an effective stop. Because of the fact that these abutting annular surfaces are beveled, this contact will not upset the metal which would cause the parts to jam.

Under many circumstances the object to be lifted is placed over the head 34, but in order to be used to lift lower objects a step projection 19 is formed on the lower part of the outer member.

The mechanism described is strong and has a great lifting capacity. Its construction is simple and inexpensive, the movable parts of its ratchet mechanism are covered so that there is no chance of the operator's fingers getting caught in it, and its parts are accessible and may be disassembled without the use of tools. A structure of preferred form and construction has been illustrated in which this invention may be used, but the inventive thought upon which this application is based is broader than this illustrative embodiment, and I therefore intend no limitations other than those imposed by the appended claims.

What I claim is:

1. A lifting jack comprising an inner member having a nut, an outer member slidably supported on the inner member, a lifting screw engaging the nut and rotatively connected with the outer member, a worm gear connected with said screw, a worm within the outer member and engaging the worm gear, said outer member having walls forming a housing for said worm and provided with bearings for the opposite ends of the worm, one of said bearings being open and extended in a direction toward the worm gear to admit the journal of the worm obliquely therewith and said outer member further having an opening through the side thereof for the admission laterally of the worm and worm gear.

2. A lifting jack comprising an inner member having a nut, an outer member slidably supported on the inner member, a lifting screw engaging the nut and rota-

- tively connected with the outer member, a worm gear within the outer member non-rotatively connected with said screw, a worm within and directly supported by the outer member rotatively, said outer member being constructed with an opening through a side thereof through which the gear and worm may be placed within the outer member, and a spring metal plate arranged to cover said opening, the outer member having grooves at the edges of said opening into which the cover plate is sprung and by which said cover plate is retained in position.
3. A lifting jack comprising an inner member having a nut, an outer member slidably supported on the inner member, a lifting screw engaging the nut and rotatively connected with the outer member, a worm gear within the outer member non-rotatively connected with said screw, a worm within the outer member, a part of said outer member forming a housing inclosing said worm having spaced walls, a circular bearing through one of said walls, and a bearing pocket in alinement therewith in the other wall, a larger bore through the first wall having its axis oblique to that of said bearing, said bearing pocket being cut away semi-cylindrically in axial alinement with said larger bore, a circular boss on the worm fitting the bearing pocket and a bore in the other end of the worm in alinement with said boss, and a spindle having parts of different diameters, the part of larger diameter being arranged to be thrust through said larger bore in said wall into the bore of the worm, the part of smaller diameter being arranged to fit the bearing in said wall into the bore of the worm, the part of smaller diameter being arranged to fit the bearing in said wall, and a shoulder formed on the spindle between the parts thereof of different diameters for engaging the inner surface of said wall.
4. A lifting jack comprising an inner member having a nut, an outer member slidably supported on the inner member, a lifting screw engaging the nut and rotatively connected with the outer member, a worm gear within the outer member non-rotatively connected with said screw, a worm within the outer member, a part of said outer member forming a housing inclosing said worm having spaced walls, a circular bearing through one of said walls, and a bearing pocket in alinement therewith in the other wall, a larger bore through the first wall having its axis oblique to that of said bearing, said bearing pocket being cut away semi-cylindrically in axial alinement with said larger bore, a circular boss on the worm fitting the bearing pocket and a bore in its other end of the worm in alinement with said boss, and a spindle having parts of different diameters, the part of larger diameter being arranged to be thrust through said larger bore in said wall into the bore of the worm, the part of smaller diameter being arranged to fit the bearing in said wall into the bore of the worm, the part of smaller diameter being arranged to fit the bearing in said wall, and a shoulder formed on the spindle between the parts thereof of different diameters for engaging the inner surface of said wall.
5. A lifting jack comprising an inner member having a nut, an outer member slidably supported on the inner member and having an upper transverse head, a lifting screw engaging the nut having an upper extension of reduced diameter provided with an annular groove, a worm gear surrounding said extension and within the outer member, non-rotatively connected with said screw, a worm within and supported by the outer member, said outer member being constructed with an opening through which the gear and worm may be placed within the outer member, and a transverse slide under said head arranged to be moved into said annular groove.
6. A lifting jack comprising an inner member having a nut, an outer member slidably supported on the inner member and having an upper transverse head, a lifting screw engaging the nut having an upper extension of reduced diameter provided with an annular groove, the under side of said head being constructed to form a pocket for the reception of the upper end of the extension, a worm gear surrounding said extension and within the outer member, non-rotatively connected with said screw, a worm within and supported by the outer member, said outer member being constructed with an opening through a side thereof through which the gear and worm may be placed within the outer member, and a transverse slide under said head arranged to be moved into said annular groove.
7. A lifting jack comprising an inner member having a nut, an outer member slidably supported on the inner member and having an upper transverse head, a lifting screw engaging the nut having an upper extension of reduced diameter provided with an annular groove, the under side of said head being constructed to form a pocket for the reception of the upper end of the extension, a worm gear surrounding said extension and within the outer member, non-rotatively connected with said screw, a thrust bearing surrounding said extension and interposed between the gear and said head, a worm within and supported by the outer member, said outer member being constructed with an opening through a side thereof through which the gear and worm may be placed within the outer member, a

transverse slide in said head arranged to be moved into said annular groove, and a non-positive stop for said slide.

8. A lifting jack comprising an inner member having a projecting portion forming a base and another portion having a cylindrical outer surface, said inner member having a nut, an outer member having a lower inner cylindrical surface fitting said outer surface of the inner member, another cylindrical surface of larger diameter and a beveled annular shoulder between said cylindrical surfaces, a collar affixed to the upper part of the inner member having a cylindrical surface fitting said larger cylindrical surface of the outer member and having a lower beveled surface in the path of movement of said shoulder to thereby engage the beveled shoulder and stop further movement of the members without upsetting the metal of the abutting parts, a lifting screw

engaging the nut and rotatively connected with the outer member, a worm gear non-rotatively connected with said screw, and a worm in mesh with said gear.

9. A lifting jack comprising telescopically engaged members, a screw for shifting one member over the other and provided with an annular groove in the end thereof, one of said members having a head provided with a seat for said end of the screw and a radial passage entering said seat and having a recess in one side thereof and a transverse slide entered in the radial passage into engagement with the annular groove in the end of the screw and provided with a hump engaging in the recess to removably secure the slide in position.

In witness whereof, I have hereunto set my hand this 21st day of December, 1918.

MALCOLM D. RIKER.
